HAMMERHEAD

Josef Pecenka, Pretoria, Hotel Fiesta, 580 Church St.,
Transvaal, Republic of South Africa

Filed Nov. 13, 1973, Ser. No. 415,373

Claims priority, application Republic of South Africa
June 26, 1973

Term of patent 14 years

Int. Cl. D8—02

U.S. Cl. D8—79

FIG. 1

FIG. 2

FIG. 3

FIG. 4

FIG. 6

FIG. 5

FIG. 1 is a perspective view of the hammerhead showing my new design;

FIG. 2 is a front elevational view;

FIG. 3 is a right side elevational view;

FIG. 4 is a rear elevational view;

FIG. 5 is a left elevational view; and

FIG. 6 is a top plan view thereof.

The broken line showing of a handle in FIGS. 1 through 5 is for illustrative purposes only.

I claim:

The ornamental design for a hammerhead, as shown and described.
